Henry J. Talge and Foster L. Talge

Application February 9, 1948, Serial No. 144,351

Term of patent 14 years

(Cl. D4—3)

To all whom it may concern:

Be it known that I, Albert M. Travis, a citizen of the United States, residing at Kansas City, in the county of Wyandotte and State of Kansas, have invented a new, original, and ornamental Design for a Floating Soap Carrier, of which the following is a specification, reference being had to the accompanying drawing, forming part thereof, in which

Fig. 1 is a perspective view of a floating soap carrier, embodying my new design.

Fig. 2 is a side elevational view of the carrier, and

Fig. 3 is a transverse cross section taken along the line 3—3 of Fig. 2.

I claim:

The ornamental design for a floating soap carrier, as shown.

ALBERT M. TRAVIS.
